C. H. DENISON, OF SPRINGFIELD, MASSACHUSETTS, ASSIGNOR TO HIMSELF, G. W. RAY, AND V. N. TAYLOR, OF THE SAME PLACE.

Letters Patent No. 79,460, dated June 30, 1868.

IMPROVEMENT IN MACHINES FOR APPLYING CLOTH PATCHES TO PAPER COLLARS.

The Schedule referred to in these Letters Patent and making part of the same.

TO ALL WHOM IT MAY CONCERN:

Be it known that I, C. H. DENISON, of Springfield, in the county of Hampden, and State of Massachusetts, have invented a new and useful Machine for Applying Cloth Patches to Paper Collars; and I do hereby declare that the following is a full, clear, and exact description thereof, reference being had to the accompanying drawings, making part of this specification, and to the letters of reference marked thereon, in which—

Figure 1, plate 1, is a perspective view of my invention.

Figure 1, plate 2, is an end elevation of said machine, with the water-pipe and valves removed.

Figure 2 is a plan view of the punch-bar, with the punches in place.

Figure 3 is a horizontal transverse section of a portion of the machine through line H I of fig. 1.

Figure 4 is a vertical section through line J K of fig. 2.

Figure 5 is a front elevation of one end of the punch-bar.

Figure 6 is a front elevation of the water-pipe and one of the sponge-tubes.

Figure 7 is a view of the clutch-lever.

Figure 8 is an end view of the punch.

Figure 1, plate 3, is another end elevation of a portion of the machine, showing its different rollers.

Figure 2 is a partial side elevation of the pinion and clutch-wheel for driving the machine.

Figure 3 is a side elevation, showing the ratchet-wheel for driving the patch-strip rollers with the gear of the collar-rollers.

Figure 4 is a side elevation, showing the ratchet-wheel and pawl for carrying the patch-strip rollers.

Figure 5 is a vertical section through line P Q of fig. 1, showing the collar-rollers and device for carrying the feeding-chain.

Figure 6 is a side elevation of the toothed segment and wheel for driving the collar-rollers and feeding-chain, with the plate of the toothed wheel removed.

Figure 7 is a front elevation of the water-outlet and sponge-tube.

Figure 8 is a vertical section through line R T of fig. 7.

Figure 9 is a vertical section of the toothed wheel and its plate through line U V of fig. 6, together with a view of the inner face of said plate, with the spring and dog attached thereto; and

Figure 10 is a side view of the toothed feeding-wheel, with the plate removed.

The nature of my invention consists in the construction of a machine for attaching cloth patches to paper collars at the places where the button-holes are to be punched, and also in a new method of preparing the said patches to be so applied by said machine.

The work of applying patches to paper collars has been done by hand, and with moist or wet paste, and, from the nature of the work, and the number of hands necessarily employed to do it, the manufacture of what is known as clothed button-hole paper collars is rendered somewhat expensive.

My invention renders the process of patching paper collars around the button-holes comparatively cheap, and much more rapid than when done by hand in the ordinary way, as one machine will do the work of from fifteen to twenty persons per day doing the work by hand.

That others skilled in the art may be able to make and use my invention, I will proceed to describe its construction and mode of operation.

I take the cloth commonly used, and prepare it in the whole piece by applying a coating of paste or some other adhesive substance to the whole of one side, and then drying it. I then cut the prepared cloth into long strips of suitable width to be made into patches as it passes through the machine, as hereinafter described.

In the drawings—

G represents the side portions of the frame of the table, having the legs, G² G³, the two side portions of the frame being connected by the piece x², which I denominate a platen, and the space bounded on three sides by the side-pieces G G and the platen x² is filled up with wood, G¹, two grooves or slots being made longitudinally therein.

Said grooves or channels extending through the platen x^7 , and along in said grooves or channels, move the feeding-chains N N, as they are operated by other portions of the machine, as hereinafter described.

The top of these side-pieces G G and platen x^7 , together with the wooden portion G, is made somewhat smooth, and upon the same plane. The lower portion of this frame is still further strengthened by means of the tie-rods G³ G⁴. To the top of this table, and over the platen x^7 , are firmly secured the uprights B B, the upper parts of which terminate in the posts A A, and they are strengthened in their positions by means of the cross-bar A³.

The shaft D, having a common eccentric or crank-connection, D', is fitted into proper bearings A¹ A¹ in the uprights A, and to one end of said shaft D is secured the wheel or disk a¹, having the projection or pin i upon its outer face, and to the other end of said shaft is fitted the clutch-collar c², which is secured to said shaft D by means of a spline and key, or by any other proper means, and said clutch-collar c² has an annular groove, b³, thereon, into which are placed the forks b³ of the clutch-lever b³, which is pivoted at b⁶ to the piece E, said piece E being bolted or secured to the upright, A.

The clutch-collar c² is so secured to the shaft D by its key and spline that it is free to move longitudinally upon the neck or small portion b¹ of the shaft D, and still, when the shaft D revolves, it shall carry with it the clutch-collar c². The hub, b, of the toothed wheel A¹, has a ratchet, e, upon its inner end, which engages with the ratchet c¹ upon the outer end of the clutch-collar c², and the said toothed wheel A¹ turns freely upon the shaft D in either direction.

The shaft A⁶ turns in proper bearings, which are made upon the opposite or back side of the uprights A A, and upon one end of said shaft A⁶ is secured the pinion A⁵, and to the other end of said shaft A⁶ is secured the drive-pulley a. The arm, a², is secured at its lower end to the rock-shaft a³, having its bearings a⁴ a⁴ secured to the standard B, the upper part of said arm a² having a longitudinal slot made therein, in which operates the pin i; and to the outer end of said rock-shaft a³ is secured the lever a⁶, which is attached or pivoted to the upper end of the connecting-rod a⁷, the lower end of said rod being connected to the projection or pin upon the reciprocating toothed segment h, this segment being hung upon a pivot, h¹, upon the side of the frame G. To the lever a⁶, and at a little distance from one end, is pivoted the rod a⁸, which rod is also pivoted to the vibrating-lever a⁹, said lever being loosely pivoted to the outer end of the shaft h¹. The shaft e⁸ turns in proper bearings e⁴ in the frame G, and to this shaft, and near one end, is attached the toothed wheel h², and the rollers or cylinders c⁸, whose diameters are greater in one direction than the other, (although this feature I find is not essential,) are firmly secured to the said shaft e⁸. The toothed collars n⁴ n⁴ are also attached to the shaft e⁸, over which collars pass the endless feeding-chains N N, and to the shaft e⁸ is also secured the toothed wheel s³, which engages with the toothed wheel e², which is secured to the shaft e⁹ working in bearings, said bearings being secured to the frame G in any suitable manner. The rollers c⁸ are firmly secured to the shaft e⁸ immediately above the rolls c⁸, and are of such diameter that the peripheries of the rolls c⁷ and c⁸ shall nearly or quite touch. To the lever or arm a⁶ is pivoted the pawl v¹, said pawl having a pin therein or projection thereon, near the lower end, against the under side of which pin or projection the spring v² impinges, as shown more fully in fig. 4, plate 3, the elastic force of the spring v² keeping the upper and sharper end of the pawl v¹ always in contact with the periphery of the ratchet-wheel c². The two shafts h² and h⁴ work in proper bearings in the standards h⁵ and h⁶, said shafts having the rolls h⁸ and h⁹ attached thereto, the former above the latter, and the bearings in the said standards h⁵ and h⁶ are elongated vertically, and the screws v⁴ are turned into the tops of said standards, the lower ends of said screws bearing down upon the shaft h², the rolls h⁸ and h⁹ being thus forced into close contact, so that, when the shaft h² is rotated, the rolls h⁹ shall cause the rolls h⁸, with the shaft h², to rotate by the friction of the rolls h⁹ against the rolls h⁸.

The toothed wheel h² has a circular cavity, h³, made upon the outer side, of sufficient depth to receive the dog h⁶ and spring h⁴, both of which are secured to the inner face of the pinion-plate h³. A small annulet, h⁵, is made around the outer edge of this cavity, said annulet being cut away, however, in two places, at h³ h³, and is so cut that there are two square ends, v² v², one directly opposite the other, across the cavity h³; while the other and opposite ends of each portion of the annulet are made curved or bevelled.

This feature is shown more fully in figs. 9 and 10, plate 3, and, by this construction, said annulet h⁵ is divided into two portions, each portion having one square end, v², and one curved-end, v³. The plate h³ is not secured to the face of the toothed wheel h², but said wheel is first placed upon the shaft e⁸, turning freely thereon, and the plate h³ is then placed upon said shaft, outside of and close to the said wheel, and said plate is then secured to the shaft e⁸, either by means of a spline and key, or by any other suitable means.

The toothed collars n⁴ n⁴ are secured to the shaft e⁸, said collars having projections or teeth, n⁵ n⁵, thereon, made in sets of two in each set, with a small space between them, these sets being at suitable distances apart around the peripheries of the said collars. The endless feeding-chains N N are made of small, thin pieces of metal riveted together, one end of a single piece being loosely riveted or pivoted between the ends of two others, two pieces which form one link, alternating with a single piece which forms the next link.

This kind of chain I do not claim as new, separately considered, as that device is old. To the upper or outer edges of the chains are secured, at proper intervals, the pins s s, and the chains N N pass over these collars n⁴ n⁴, between the teeth or projections n⁵ n⁵; each set of said teeth projecting into the chain between two adjacent double links, and upon each side of every single link, these sets of teeth or projections serving to keep the chains in position upon the collars, and also to give the chains their longitudinal movement along the table. The pulleys n n upon the shaft n⁶, said pulleys having a flange upon each end, serve to assist in keeping the chain in its proper place, and render its movement easier; and the pulleys n¹ n¹, underneath the table, also serve the same purpose, and, if the chain should by any means get stretched or lengthened, said pulleys n¹ n¹

may be lowered in the vertical slot made in the rods n^2 n^3 , and secured at any desirable elevation by tightening the screws n^4 .

The connecting-rod D^3 is attached at one end, D^2 , to the crank D^1 upon the shaft D , and the lower end, d^3 , is attached to the plunger D^5 , the connection being made by means of a pin, d , passing through the two eyes D^4 D^4 upon the upper end of said plunger D^5 , and also through the eye d^4 at the lower end of said connecting-rod. The two pieces or elongated projections C C are cast upon and with the uprights A A , and upon the inside of each piece C is made the vertical groove f , which may be of any desired form in its cross-section, and the two vertical edges of the plunger D^5 are made of a corresponding form, to fit properly and move freely in the grooves f f . At the lower end of the plunger D^5 is the plate D^6 , which may be cast solid with the plunger D^5 , and to this plate D^6 are attached the pieces F F , connected with each other by the bar F^1 , said bar F^1 having two longitudinal slots h^3 h^3 made therein. The sponge-tube consists of a pipe, d^5 , open both at top and bottom, and two of them, one near each end of the bar F^1 , provided with the elongated inclined pans or ducts d^5 , and, at a proper distance from the lower end, the piece, o^4 , is secured to the pipe d^5 , said piece terminating in a projection, o^5 , with a screw-thread cut thereon. The projection o^5 is inserted through the longitudinal slot h^3 in the bar F^1 , and the thumb-nut o^6 , with a screw-thread cut thereon, is turned upon the threaded projection o^5 , and tightly against the back side of the bar F^1 thus securing the sponge-tube d^5 to said bar F^1 .

Upon the upper edge of said bar, and behind each sponge-tube, is a small projection, o^1 , having a hole therein, in which is cut a screw-thread, and the rod o^8 , with a screw-thread cut upon its lower end, is inserted into the said hole in said projection, and, as the rod is turned either in or out, it is elevated or depressed in its position. The box g is placed between the uprights A A , and behind the projections C C , said box having an orifice through the bottom into the pipe g^1 , the other end, g^2 , of said pipe being either stopped in any convenient manner, or opening into said box g . A portion of the pipe g^1 extends out over the sponge-tubes d^5 , immediately over which are the outlets g^3 , placed in the pipe g^1 at g^2 .

In the outlets g^3 are placed the valves m^1 , having an annular bevelled shoulder upon the upper portion, to fit the bevelled portion of the outlet, which constitutes the seat of the valve, and the upper part of said valve, m^1 , terminates in a vertical stem, with a shoulder, m^3 , at the bottom. Upon this stem is placed a spiral spring, which bears against said shoulder, and keeps the valve down against its seat or bearing in the outlet g^3 . This valve, however, may be constructed of any desirable form, or as poppet-valves are usually made.

A small vertical slot is made in the back part of the outlet g^3 , through which protrudes the arm m^4 , which arm may be cast or made solid with the main part of said valve m^1 , and said arm is sufficiently long to be struck and forced upward slightly by the top of the rod o^8 , in its upward movement, the spiral spring forcing the valve m^1 down against its seat as soon as the rod o^8 falls to its place.

The punch-bar F^3 is made of suitable width and thickness to secure sufficient strength, and has the rectangular shoulders e^5 , which fit against the corners of the uprights B B , to which said bar is secured by bolts passing through the slot e^4 . Said bar is further strengthened by two longitudinal ribs, e^1 e^2 , between which is made a longitudinal slot, F^4 , the front side of said bar being made perfectly plane.

The punches consist of a suitable piece, e , the back side of which is made plane, and fits well the front side of the bar F^3 , and upon the back side of said piece e is a projection, e^6 , prismatic in form, and should fit well the width of the slot F^4 in the bar F^3 .

Upon the outer end of said projection e^6 is cut a screw-thread, e^7 , upon which fits the thumb-nut e^8 , having a screw-thread cut therein.

The piece e has an enlarged projection, F^4 , thereon, through which is a vertical hole, which hole may be prismatic, oval, or other form in its cross-section. I prefer a prismatic form.

The lower portion of the piece e projects forward, as shown at x^3 , and an orifice, x , extends entirely through the lower portion, x^3 , in a horizontal longitudinal direction. This orifice is quite small vertically, but is a little wider than the largest diameter of the die.

The punch D^7 is made prismatic at its middle portion, to fit well the prismatic hole in the part F^2 .

A flange, x^2 , is made upon the upper end of the punch D^7 , and the part between said flange x^2 and the prismatic portion is somewhat smaller, around which part is placed a spiral spring, x^4 , the upper end of which bears against the flange x^2 , while the lower end rests upon the top of the part F^2 ; the action of said spring thus keeping the said punch always in its highest position, except when said punches are forced downward by the plunger and plate D^5 .

The lower end of the punch is made oval, or of any desired shape, and of sufficient length to pass through the aperture, e^2 , in the part x^3 , and reach the collar lying upon the platen x^7 , said aperture e^2 being made of a size to fit nicely the end of the punch or die e^6 . This end of the punch e^6 I denominate the die, and the part x^3 , with the aperture e^2 , I denominate the counter-die, and it is better that the said counter-die should be tempered quite hard, while the die e^6 should be left soft or annealed, in order that when said die e^6 becomes dull, it may be upset and sharpened again.

A suitable piece of metal, D^9 , is secured to the upper and front part of the projection x^3 , and is bent forward and upward to the point o , and is then bent downward and backward to the lower edge of the front part of the projection x^3 . At the forward and bent extremity o of this piece, D^9 , a long orifice is made, which is a little wider than the die e^6 .

The supports f^1 f^1 , each having the flat part, f^2 , at the lower end, are secured to the uprights B B , or to any other convenient part of the machine, the other end extending up over the table or platen x^7 .

A spiral spring is placed upon the spindle-end of the support f^1 , and the spool f^3 is placed thereon, and held in place by a pin, x^6 , or by a nut, as may be desirable.

One end of the spiral spring bears against the shoulder f^6 , while the other end bears against the spool f^3 , thus creating friction, which prevents the spool from turning too easily upon its spindle.

Another support, f^6 , is secured to one of the projections C , and having a spindle thereon, which supports in like manner the middle spool, f^4 , which is kept from turning too freely by means of a spiral spring similar to the others.

Having thus described the construction of my machine, I will proceed to describe the mode of its operation.

The cloth, which has been properly prepared with paste or other adhesive substance, and dried in the piece, is cut into strips a little wider than the diameter of the die, so that they may readily pass through the slot or orifice x , and said strips are then wound upon the spools f^3 f^4 , which I do by proper machinery. The loose end of each strip is then inserted into the opening o , and pushed through the orifice x , with the pasted side down, is passed out, up, and between the rolls h^8 and h^9 , and from thence it would be better that the strips should pass over a drum or pulley worked by the other machinery, although this is not actually necessary to the successful operation of the machine.

The upper rolls, h^8 , are pressed down upon the rolls h^9 , by turning down the screws i^4 upon the shaft r^2 .

The lower end of each tube d^3 is filled with a suitable piece of sponge or similar material, which is left protruding a little below the end of the tubes, and water is placed in the box g , and fills the pipes g^1 .

Power is applied to the pulley a and the shafts A^6 and pinion A^5 , revolving, cause the toothed wheel A^4 to revolve.

If the clutch-handle b^7 be thrust in towards the machine, the clutch C^2 engages with the ratchet c^1 , upon the hub of the toothed wheel A^4 , and, as the said clutch is keyed to the shaft D , the toothed wheel A^4 causes the said shaft to revolve, and a reciprocating vertical motion is given to the plunger and plate D^6 with the bar F^1 and sponge-tubes d^3 , the two water-tubes being secured in the slots h^3 , while the middle tube may be permanently attached to the bar F^1 by screws or otherwise.

The pin i , in the wheel a^1 , in its revolution, operates in the slot i^1 , and causes the arm a^2 , rock-shaft a^3 , and arm a^6 to perform a reciprocating rotary motion, said motion being communicated to the toothed segment k . The motion of this segment causes the toothed wheel k^2 to perform also a reciprocating rotary motion a little more than half way around, or a little more than half a revolution, said toothed wheel k^2 turning loosely upon the shaft e^8 during the downward movement of the rod a^7 , and when said rod has finished its downward motion, the point of the dog k^6 is forced into one of the spaces h^5 , and, as the rod a^7 and toothed segment perform their upward movement, the square end of the annulet k^4 impinges against the dog k^6 , and forces it, with the plate k^3 and shaft e^8 , to make half a revolution. This motion, through the toothed collars n^4 n^5 , upon the shaft e^8 , gives an intermittent horizontal movement to the chains N N , and the distance of each movement of the chain is equal to half the circumference of the said collars n^4 —the distance between the centres of the dies e^4 and sponge-tubes d^3 —the distance between the pins s s and the semi-circumference of said collars n^4 all being equal.

If a collar be laid upon the table G^1 , and across the two chains N N , at the next forward movement of the chains, two of the pins s s move the collar along upon the table until it stops at the proper point under the sponge-tubes d^3 , and when the said tubes next move downward, the sponges in their lower ends, being dampened by the water from the pipe g^1 , just touch the collar at the three points where the button-holes are to be punched, and dampen the collar at those parts. As the plunger-plate D^6 , bar F^1 , and tubes d^3 move up again, the upper end of the rod a^6 , being properly adjusted, just touches the under side of the arm m^4 of the valve in the outlet g^3 , slightly raising it, and a drop or more of water drops from the outlet upon the sponge in the tube d^3 . In this way the sponge may be kept at any desirable and uniform degree of dampness.

While the plunger and tubes d^3 are moving up, the chains N make another forward movement, and the parts of the collar which have been dampened are brought immediately under the orifice of the counter-die e^8 .

As the arms a^6 and a^8 move upward, the pawl r^2 , upon the arm a^6 , causes the ratchet-wheel c^1 to make a rotary movement, and the strip L , being pressed between the rolls h^8 and h^9 , is unwound from the spool f^3 , pulled through the orifice x a little more than the width of a patch, and, at the next downward movement of the plunger-plate D^6 , it strikes the tops of the punches D^7 , and forces the die e^4 down through the strip L and aperture e^2 , and the end of the die presses upon the parts of the collar which have been dampened, and presses the patch, which the die e^4 has cut from the strip L in its downward passage, hard upon the dampened places on the collar, where it remains, and as the collars pass out between the rolls c^7 and c^8 , the patches are pressed harder upon the collars, and make them smooth and uniform in their appearance.

In applying patches to collars of different lengths, the two outer or end sponge-tubes may be moved in or out, by loosening the nuts e^3 , moving the tubes to the desired position, and tightening the nuts again; and if the tube d^3 is not immediately under the outlet g^3 , the water may drop into the side pans or ducts d^7 , and run from thence into the tube d^3 , and the nuts e^3 , upon the two end punches, may be loosened, the punches moved in or out to their desired position in the slot F^4 , and the nuts tightened again.

Each intermittent rotary movement of the rollers h^8 and h^9 pulls the strip L through the slot x sufficiently to move the place in the strip L where the last patch was cut out away from under the die e^4 , so that the next downward movement of the said die may cut out a whole patch.

By dispensing with the pins s s , upon the chains N N , I am enabled to apply patches to paper in the roll, strip, or sheet, and cut the collars from such paper, after said patches have been applied.

Instead of using the spiral springs x^4 to raise the punch-dies e^4 out of the orifices e^2 in the counter-dies x^3 , I propose to make a longitudinal slot on the under side of each end of the plunger-plate D^6 , and a transverse slot in the middle, and insert the flanges x^2 , upon the tops of the punches, into the said slots, so that the plate D^6 , in its downward and upward movements, shall both force the said punches into and withdraw them from the orifices e^2 , in the counter-dies.

Having thus described my invention, what I claim as new, and desire to secure by Letters Patent, is—

1. The combination of the plunger or plate D⁶, with the bar F¹ attached thereto, the stamps e and sponge-tubes d⁵, all constructed and operating substantially as herein described, and for the purposes set forth.
2. The combination of the plunger or plate D⁶, with the bar F¹ attached thereto, the stamps e, the sponge-tubes d⁵, and the water-pipe g¹ and box g, when constructed and operating substantially as described, and for the purposes specified.
3. The stamps e, having the dies e¹, counter-dies x³, and the passage x therein, all constructed substantially as herein described and specified.
4. The combination of the stamps e, having the dies e¹, counter-dies x³, and the passage x therein, with the platen x⁷, when constructed and operating substantially as described, and in the manner set forth.
5. The combination of the wheel a¹, with the projection i thereon, vibrating-arm a², rock-shaft a³, lever a⁶, rod a⁸, arm a⁹, ratchet-wheel and pawl e³ i³, and rolls h⁸ h⁹, for the purpose of moving the strips under the dies e¹, substantially as described.
6. The bar F¹, having the slot F¹ therein, in combination with the stamps e, having the projections e⁶ thereon, all constructed and arranged substantially as herein described and set forth.
7. The sponge-tubes d⁵, in combination with the water-pipe g¹, having outlets g³ therein, all constructed and operating substantially as herein described, and in the manner specified.
8. The combination of the sponge-tubes d⁵, adjustable rod o⁸, and valve and valve-arm m¹, when constructed substantially as described, and operating in the manner set forth.
9. The sponge-tubes d⁵, having the side pans d⁷ thereon, and the adjusting projection o⁵ and its nut o⁶, all constructed and operating substantially as described, and in the manner set forth.
10. Applying cloth patches to paper or paper collars as herein described, that is to say, by first dampening the paper or collar at the places where the patches are to be applied, and then pressing said patches thereon by means of a punch or die, which, in its descent, cuts the patch from cloth which has been previously made adhesive upon one side, by a suitable preparation, and then dried, said prepared cloth being fed or moved automatically to or under the dies, all substantially as described.

In testimony whereof, witness my hand, this 1 day of June, A. D. 1868.

C. H. DENISON.
